DIPPER TRIP CONTROL

George E. Miller, Findlay, Ohio, assignor to The Buckeye Traction Ditcher Company, Findlay, Ohio, a corporation of Ohio

Application September 27, 1938, Serial No. 231,948

4 Claims. (Cl. 214—146)

This invention relates to trip controls for the buckets or dippers of excavating or material transferring machines, and particularly to such a control of the fluid pressure type.

5 The primary object of the invention is the provision of a simple and efficient control of this character which is easy and inexpensive both to apply to a machine and to operate, and enhances the practicability and commercial value of machines with which it is associated.

10 The invention is fully described in the following specification and one embodiment thereof illustrated in the accompanying drawings, in which—

15 Fig. 1 is a fragmentary side elevation of a dipper type excavating machine with the trip control feature embodying the invention associated therewith;

20 Fig. 2 is an enlarged fragmentary section on the line 2—2 in Fig. 1;

Fig. 3 is a fragmentary detail, in plan, of the trip line and its mounting means;

25 Fig. 4 is a fragmentary plan of the machine with the trip control feature embodying the invention in association therewith;

Figs. 5 and 6 are different vertical sectional details of one form of manual control employed in connection with the invention; and

Fig. 7 is a horizontal cross-section on the line 30 7—7 in Fig. 5.

Referring to the drawings, 1 designates an excavating machine of the dipper type, 2 the boom thereof, 3 the dipper, and 4 the dipper stick which has a rack and pinion connection with the boom and has its movement controlled in any suitable manner as well understood in the art. In the present instance the hoist cable 5 for the dipper winds on a control drum 6. This drum is driven in any suitable manner, as through a gear 7 and such drive is controlled by a clutch which is normally disengaged, and is engaged when one side of the associated vacuum cylinder 8 is open to a vacuum source, as well understood in the art. The cylinder 8 is in communication with a vacuum tank 9 or other suitable source through tubes 10 and 11 and an interposed manual control 12.

The trip line 15 for the trip 16 of the dipper 3, which may be of any suitable well known pull type, passes, in the present instance, up from the dipper over an idler sheave 17 on the dipper stick shipper shaft 18 carried by the boom, thence passes back around an idler sheave 19 anchored near the inner end of the boom and then forward to and winds on and is anchored to a drum

20 fixed on the shipper shaft. This shaft, which is driven in any well known manner, as through a sprocket 21 thereon, has a rack pinion 22 fixed thereon and in driving engagement with a rack bar 23 on the dipper stick whereby a 5 turning of the pinion will shift the stick. The rack pinion and drum 20 turn in unison so that the trip line 15 is paid out or slack therein taken up in accordance with the outward and inward movements of the stick. No novelty is claimed 10 for this.

The present invention resides in the trip control for the trip line 15 and includes, in the illustrated embodiment, a vacuum cylinder 25 carried by the boom at its inner end and a piston 26 15 therein from which a stem 27 extends and carries the sheave 19. An outward vacuum actuated movement of the piston relative to the sheave imparts sufficient pull on the trip line 15 to release the dipper trip. 20

The outer end of the cylinder 25 is connected to the vacuum line 11 through the pipe 29 and control 12. This control, in the present instance, is such that when the control handle 30 thereof is in neutral position, as shown in Figs. 5 and 25 6, the communication between the vacuum source and both cylinders 8 and 25 is closed, and such communication is respectively open to one or the other of said cylinders when the handle is moved in one or the other direction from neutral position, so that the pistons in the two cylinders 30 may be selectively operated but not simultaneously.

One control of this type which is suitable for the purpose, but which in itself forms no part of 35 this invention, is illustrated in Figs. 5, 6 and 7. This control in itself is old, being purchased on the market, and will be described only sufficiently to enable its operation in connection with the present invention to be understood. This control includes a casing 31 having upper and lower sections divided by a partition member 32. The lower compartment is provided with four vertically disposed bores 33, 34, 35 and 36 forming valve chambers which are rectangularly arranged with the chambers 33 and 34 diagonally disposed and each in communication with a vacuum tube 11 and with the chambers 35 and 36 likewise diagonally disposed and in communication with an air inlet tube 37. The partition 50 member 32 has an opening therethrough from the top of each of said valve chambers 33, 34, 35 and 36 into a respective chamber in the upper section of the control, the interior of said section for such purpose being centrally divided one 55

way by a vertical partition 38 and centrally the other way by a vertical partition 39. A separate valve 40 is disposed in each of said valve chambers and is normally held seated against the partition 32 to close the respective opening therein by an associated spring 41.

A stem 42 projects upward from each valve 40 within the associated compartment of the upper section in position to be acted upon by respective fingers 43 of the hand control lever 30. This lever is fulcrumed in the partition 38 crosswise of the partition 39. The lever 30 has four fingers 43, two at one side of the fulcrum and two at the other side, and positioned to act on the upper ends of the respective valve stems 42.

Each of the branch vacuum tubes 10 and 21 is connected to a respective pair of air and vacuum chambers, for instance, the tube 10 connects with the chambers 33 and 35 through a passage 45, which extends up through the casing into the partition 38 and thence opens crosswise of such partition into each of the upper compartments with which the chambers 33 and 35 are adapted to communicate when their respective valves are open. Likewise the vacuum tube 29 is connected to the chambers 34 and 36 through a passage 46 located in the partition 38, which passage communicates at its upper end with both of the upper compartments with which such chambers 30 connect, and with said chambers when their respective valves are open.

When the control lever 30 is in its neutral position, as shown in Fig. 5, both air valves 40, which are disposed in the respective chambers 35 and 36, are held slightly open so that air under atmospheric pressure will be admitted through the line 37 and communicating air chambers 35 and 36 to both branch vacuum tubes 10 and 29 to relieve any vacuum action therein. 40 When the lever is rocked in either direction from neutral position, one or the other of the branch lines 10 and 29 is closed to the atmosphere by reason of the closing of the associated air valve, and is open to the vacuum source by reason of the opening of the associated vacuum valve 40.

Such movement of the control lever 30 also further opens the air valve on the same side of the lever as the vacuum valve, which is being opened, but this is immaterial as the other branch line with which such air valve is associated should be in communication with the atmosphere.

It is thus apparent that when the control lever 30 is in neutral position, both cylinders 8 and 25 are closed to the vacuum source and open to the atmosphere and that a rocking of the lever in either direction will open the vacuum source to one or the other of said cylinders and close the air communication therewith, thus effecting an application of the drum clutch in one case and 60 the dipper trip in the other case. It is apparent that by providing a single control for the hoisting drum clutch and the dipper trip, the operator may move the control handle 30 in one di-

rection from neutral to effect a hoisting of the dipper to proper position for dumping and may then after swinging the lever to neutral position, effect a tripping of the dipper by simply swinging the control lever to tripping position without removing his hand from the lever, thus facilitating the hoisting and tripping actions.

I wish it understood that my invention is not limited to any specific construction, arrangement or form of the parts, as it is capable of numerous changes without departing from the spirit of the claims.

Having thus described my invention, what I claim as new and desire to secure by United States Letters Patent, is:

1. In combination in a machine of the class described, a dipper, a hoisting means for said dipper including a hoist drum, a vacuum actuated drive clutch means for said drum, vacuum actuated trip means for said dipper, a vacuum source adapted to have communication with said clutch means and said trip means, and means normally closing the communication between said source and each of said clutch and trip means, and operable to selectively open the communication between said source and either of said means.

2. In a machine of the class described, in combination, a hoist drum control clutch, a dipper trip means and a pneumatic operating means common to both said clutch and trip means and having a unitary control member operable by movement from neutral to selectively cause engagement of said clutch or an actuation of said trip means.

3. In combination in a machine of the class described, a dipper having a dump trip, a hoisting means for the dipper including a hoist drum, a differential fluid pressure actuated drive clutch for said means, a differential fluid pressure actuating means for the dipper trip, a differential fluid pressure source in communication with said drive clutch and trip actuating means, and means having a control member and operable to close the source communication to both said drive clutch and trip actuating means when the control member is in one position and to selectively open said source communication to said drive clutch and trip actuating means when the control member is in different predetermined positions of its movement from neutral.

4. In a machine of the class described, in combination, a hoist drum control clutch having an operating cylinder and plunger in connection therewith, a dipper trip means having an operating cylinder and plunger in connection therewith, a differential fluid pressure source in communication with each of said cylinders for operating the respective clutch and trip means, and means including a single control member operable to close both of said communications or to selectively open either communication.

GEORGE E. MILLER
